[57] CLAIM

The ornamental design for a line guide for fishing rods, as shown and described.

DESCRIPTION

FIG. 1 is a top, front and one side perspective view of a line guide for fishing rods showing our new design; FIG. 2 is a side elevation of one side thereof;

FIG. 3 is a right side elevation of one side thereof, the side opposite being a mirror image;

FIG. 4 is a top plan view thereof;

FIG. 5 is a bottom plan view thereof;

FIG. 6 is a top, front and one side perspective view of a second embodiment thereof;

FIG. 7 is a side elevation of one side thereof, the side opposite being a mirror image.

FIG. 8 is a front elevation thereof;

FIG. 9 is a top plan view thereof; and

FIG. 10 is a bottom plan view thereof.
